UNITED STATES PATENT OFFICE

PERCY A. ROBBINS, OF HIGHLAND PARK, ILLINOIS

SOUND-TRANSLATING CHAMBER

Application filed September 14, 1927. Serial No. 219,548.

This invention relates to chambers in which sounds are recorded or translated for mechanical or electrical reproduction and which are commonly known as "studios".

5 The usual practice in studios is to generate sounds by setting the air particles in motion. These motions are propagated through the atmosphere, being directed to diaphragms which translate the sound waves into mechanical motion of the diaphragms for recording or for further translation and transmission.

This entire method of propagating and translating sounds is inefficient because air 15 is an attenuated medium of light mass and can only transmit the required sound energy by virtue of high velocities imparted to the air particles, that is, each vibration must be of great amplitude in order that the air particles may attain the necessary velocity to transmit the impressed sound energy.

Sound producing instruments vibrate at comparatively low amplitudes, and in most cases attempts to increase the amplitudes of vibrations result in the production of overtones, because the inertia of the vibrating reeds, or 25 strings or vocal chords, as the case may be, tends to damp the increased amplitudes and break up the vibrating structure into an increased number of nodes and anodes.

Thus although the performers of instrumental or vocal music or sounds possess a surplus of power, they cannot use that surplus power beyond a certain limit because of the 35 difficulty in avoiding the production of undesirable overtones and harsh noises.

In a like manner the conversion of the air vibrations into vibrations of a diaphragm is inefficient because the mass of the diaphragm 40 is necessarily great, for it must be made of available materials of construction and must possess certain structural strength regardless of its function to vibrate freely.

Obviously then, in order to increase the 45 sound energy which may be satisfactorily emitted by sound producing instruments and translate the sound into mechanical movements of a diaphragm, the medium through which the sound is propagated from the 50 source to the diaphragm should be a medium

of comparatively great mass, and a dense gaseous medium is best adapted for the purpose.

My object, therefore, is to devise means for utilizing this principle in the manufacture 55 of phonograph records, or in radio broadcasting.

I attain my object by employing as a studio a chamber provided with an air lock for the entrance and exit of performers. Within 60 this chamber an air pressure is maintained which is greater than normal atmospheric pressure.

As the performers in the denser atmosphere of the studio are forced to breathe in an excess 65 of oxygen per cubic foot of air inspired, it will be advisable to modify the atmosphere by the introduction of a suitable proportion of an inert gas such as helium or an excess of nitrogen, thus avoiding the danger of excessive oxydization of the blood and lung tissues.

To avoid confusion of sounds due to reverberations and reflections within the studio it is essential that the walls and ceiling 75 of the studio be non-reflecting. This can be accomplished most effectively by hanging the walls with strings or ropes or other like strips of soft flexible material, preferably arranged in a series of rows spaced from one 80 another and the walls of the chamber, and by suspending vertically from the ceiling a great number of strings or ropes, preferably of unequal lengths spaced at random.

While I contemplate the use of the common types of broadcasting microphones and phonographic recording devices located in the usual manner within the studio, there are certain advantages to be gained by not having 85 this apparatus so located.

I therefore incorporate the translating diaphragm as a part of the studio wall, and by this means remove from the studio all but the exposed face of the diaphragm. Noises emanating from the recording or translating devices are thus eliminated from the studio, and the presence in the studio of operatives whose duty it is to regulate the recording and translating devices is not necessary.

In some cases it is desirable that photo- 100

graphs shall be taken of the performers while in the studio, and as the space within the studio will be more or less restricted, and the clicking of cameras will be objectionable noises, it is very desirable that the cameras and their operatives be outside of the studio. I accomplish this object by providing windows set in air tight, adjustable, spherical frames, which may be twisted about into position satisfactory to the photographer.

The intensive flood-lighting necessary for satisfactory photographic results, produces a great deal of heat, and as it is most desirable that this heat be excluded from the studio I arrange suitable windows for projecting light into the studio from outside sources.

The space within the studio being restricted it is necessary to provide a means for changing the air and I accomplish this by means of an exhaust valve which is connected to the studio through a muffled passage.

The invention is hereinafter more fully described and is illustrated in the accompanying drawings in which

Fig. 1 is a diagrammatical sectional view of apparatus constructed in accordance with my invention;

Fig. 2 a sectional detail showing the method of securing an adjustable window in position;

Fig. 3 a vertical sectional detail of part of the wall and ceiling of the chamber illustrating the method of draping to prevent sound reflection.

In the drawings like numerals of reference indicate corresponding parts in the different figures.

1 is the sound translating chamber, which will usually be formed of metal, or otherwise constructed so as to contain air at super-atmospheric pressure. This chamber is provided for the purpose of entrance and exit with an air lock 2 of known type. As such devices are well known in the art, a specific description of its details is omitted.

Means are provided for introducing air under pressure into the chamber 1, and for rendering this pressure constant. For this purpose I provide the gasometer 3 which may be of any known type. From this gasometer a pipe 4 leads to the interior of the chamber 1. This pipe is provided with a controlling valve 5, preferably within the chamber 1. A valve controlled outlet 6 is also provided, whereby air within the chamber may be allowed to escape under the control of any one within the chamber.

With the interior of the gasometer communicates a pipe 7, preferably provided with a check valve 8 to prevent back flow. A second pipe 9 is provided also communicating with the interior of the gasometer, preferably through part of the pipe 7. This pipe is also provided with a checkvalve 10. Through one of these pipes air under pressure may be introduced into the interior of the gasometer,

while through the other any gas which it may be desirable to use to modify the atmosphere of the chamber may be introduced.

The sound translating diaphragm 11 is set in an opening 12 formed in the wall of the chamber so that there is no need for the presence in the studio of any operatives whose duty it is to regulate the recording and translating devices. Certain possibilities of the introduction of disturbing noises are thus eliminated.

As it is sometimes desired to take photographs of performers within the chamber and, as it is very desirable that noise producing instruments be kept outside the studio, I provide one or more windows in the studio, such as illustrated in Fig. 2. In an opening in the wall of the chamber 1 is fitted a frame 13, in which frame is formed an opening 14 having a segmento-spherical wall. In the opening 14 is fitted a frame 15 having an opening therein fitted with the glass frame 16. The frame 15 will have an air tight fit with the frame 13, and may be set up to incline the pane 16 in any desired position. The frame 13 must necessarily be made in halves, secured together by the bolts 17, in order that the frame 15 may be positioned therein.

Trouble, due to sound reflection, is likely to be increased by the dense atmosphere, hence I employ the special means for breaking up reflections illustrated in Fig. 3. Brackets 18 are secured about the wall of the chamber. From these brackets are hung a series of rows of strings or ropes 19 or other like strips of soft flexible material. From the ceiling are hung a series of strings or ropes of soft flexible material, preferably of different lengths, so as to present any irregular under surface, if such it may be called.

From the above description the method of use of the sound translating chamber will be reasonably clear. A sufficient amount of atmospheric air is introduced into the chamber at approximately the desired pressure, which will usually be less than thirty-five pounds per square inch. This air will be modified by the introduction through one of the pipes connected to the gasometer of a suitable proportion of an inert gas such as nitrogen or helium. As may be necessary, air is allowed to escape through the pipe 6, the gasometer maintaining the pressure until a further supply of air and inert gas is supplied through the gasometer. The performers enter or leave from time to time through the air lock the operation of which, of course, assists in the changing of the air within the chamber.

From the above description it will be seen that I have devised a sound translating chamber, which will satisfactorily attain the objects of my invention as set out in the preamble to the specification.

What I claim is:

1. A studio in which sounds may be produced for record or translation, comprising a closed chamber containing air under a pressure greater than that of the air outside the chamber, and provided with a vibratable diaphragm exposed at one side to the pressure within the chamber and at the other to the atmosphere outside the chamber.
- 10 2. A studio in which sounds may be produced for record or translation, comprising a closed chamber containing air under a pressure greater than that of the air outside the chamber and provided with a window adjustable to positions normal to the light rays passing through it, whereby reflection and refraction of such rays may be avoided.
- 20 3. A studio in which sounds may be produced for record or translation, comprising a closed chamber containing air under a pressure greater than that of the air outside the chamber and having its walls draped with strips of soft flexible material suspended vertically by their upper ends.
- 25 4. A studio in which sounds may be produced for record or translation, comprising a closed chamber containing air under a pressure greater than that of the air outside the chamber and having its ceiling draped with strips of soft flexible material suspended vertically by their upper ends.

Signed at Highland Park, Ill., this 20th day of September, 1927.
